TRANSFER MECHANISM FOR A TOTALIZER

Albert S. Wheelbarger, Dayton, Ohio, assignor,
by mesne assignments, to Central United
National Bank, Cleveland, Ohio, as trustee

Application February 18, 1932, Serial No. 593,743

8 Claims. (Cl. 235—134)

This application is a continuation in part of the patent of Albert S. Wheelbarger and Grover C. Coil, number 1,876,118, dated September 6, 1932. In the said patent the totalizer wheel of 5 lower denomination is provided with a transfer tooth which cocks a transfer arm while the totalizer is in mesh with the actuating segments therefor and after the totalizer has been disengaged from the actuating segments this arm is spring 10 actuated to advance the totalizer wheel of next higher denomination one unit. In cases, however, where a large number of transfers will take place practically simultaneously, as where for instance the operator adds one to the number previously standing on the totalizer wheels, say \$99,999.99, no less than seven transfers must take 15 place almost simultaneously. If the machine is made very rugged and out of heavy parts, this transferring in the case cited might require considerable energy and I, therefore, deemed it advisable to eliminate the spring to actuate the transfer mechanism and to substitute in place thereof a series of staggered cams which will successively engage the transfer arms so that the transfer 20 from units to tens will take place and immediately thereafter the transfer from tens to hundreds, etc. Each one of these arms has a separate cam and all of the cams are connected together so that the correct sequence will take place and each 25 of the transfer arms will be positively actuated by means of these cams.

In the drawings:

Fig. 1 is a side elevational view of one side of the machine with the casing removed;

Fig. 2 is a detailed elevational view of a part of the mechanism to actuate the totalizer cams;

Fig. 3 is a side elevational view, partly in cross section, of the left hand side of the totalizer shown in Fig. 4;

Fig. 4 is a front elevational view, certain parts being fragmentary, of the totalizer;

Fig. 5 is an elevational view, partly in cross section, on the line 5—5 of Fig. 4 looking in the direction of the arrow;

Fig. 6 is a cross sectional view on the line 6—6 of Fig. 3; and

Fig. 7 is a side elevational view of one of the transfer arms and associated mechanism.

A crank 1 is secured to a shaft 2 which carries 50 a gear 3 which drives a gear 4 secured to a shaft 5 which carries a gear 6 which drives a gear 7 secured to a shaft 8, which shaft has secured thereto a box cam 9 provided with a cam race 10.

The side wall 11 of the machine carries a fixed 55 pin 12 which extends within the bifurcation 13

of the lower portion of a bar 14 which carries a pin 15 on which is mounted a roller 16. The pin 12 serves as a guide for the bar 14. The roller 16 extends within the cam race 10 and as the box cam 9 rotates in the direction of the arrow 5 shown in Figs. 1 and 2 the bar 14 will be first raised and then lowered. The upper end of the bar 14 is provided with a pin 17 which is carried by an arcuate rack 18 pivoted on a shaft 19. The arcuate rack 18 meshes with and drives a 10 pinion 20 mounted on a stud shaft 21 carried by the side wall 11. The shaft 21 is also provided with a pinion 22 which meshes with a pinion 23 mounted on a shaft 24 which is carried by arms 25 and 26. The pinion 23 drives a 15 pinion 27 secured to a cam shaft 28. The shaft 28 is supported in the side walls 29 of the totalizer which is moved back and forth so as to bring the totalizer wheels into and out of mesh with the totalizer actuating segments 30, as is well 20 known in the art but which mechanism forms no part of this invention and need not be described. The arms 25 and 26 are necessary inasmuch as the axis of the shaft 21 is a fixed axis for the shaft is supported on the side wall 11 25 whereas the axis of the shaft 24 is movable for it partakes of the movement of the totalizer as the frame is moved towards and away from the actuating segments 30. The gearing arrangement described is such that when the crank 1 is 30 rotated one time, the cam shaft 28 will rotate approximately 324 degrees in a clockwise direction as viewed in Figs. 3 and 5, which rotation is caused by the elevation of the bar 14. When the bar 14 is lowered by the cam race, the shaft 28 will 35 be rotated in an anti-clockwise direction as viewed in Figs. 3 and 5 the same number of degrees, or back to its home position. It will be noted from viewing Fig. 2 that the lower portion of the cam race as viewed in the said figure forms 40 an arc of a circle for something less than 180 degrees and there is, therefore, a dwell between the clockwise and anti-clockwise rotation of the shaft 28, which dwell takes place while the totalizer wheels are in mesh with the actuating segments 30 45 thereof. In other words, the shaft 28 is rotated approximately 324 degrees prior to the time that the totalizer is brought into engagement with its actuating segments 30, there is then a considerable dwell while the totalizer 50 wheels are in engagement with the totalizer actuating segments 30, the totalizer is then disengaged as will be hereafter described and thereafter the shaft 28 is rotated approximately 324 degrees in an anti-clockwise direction so as to 55

effect the carrying operation after the totalizer wheels have been disengaged from their actuating segments 30.

On the front of the box cam 9 as viewed in Fig.

5 1 is a cam race 31 which receives a roller 32 carried on a stud 33 secured to a lever 34 pivoted on a stud 35. A lever 36 is pivoted on a shaft 37 carried by the side walls 11. The lower end of the lever 36 is provided with a pin 38 and the 10 upper end of the lever 34 is provided with a pin 39 which are connected by a spring 40. The shaft 37 has secured thereto two arms 41 which are bifurcated at their upper ends and receive a bar 42 which extends between the two side walls 15 29 of the totalizer. By this means the totalizer frames are shifted first towards the actuating segments 30 and then, after the actuating segments 30 are actuated, the totalizer frame is moved to its outer position so as to disengage the 20 totalizer wheels from the actuating segments 30.

When the arms 41 have been rotated counter-clockwise so as to move the totalizer frames 29 inwardly the totalizer wheels 43 are brought into mesh with the actuating segments 30 and when 25 the actuating segments are rotated an amount corresponding to the amount set up on the cash register, as is well known in the art, the totalizer wheels 43 will be correspondingly actuated. These wheels are loosely mounted on the shaft 44 and 30 each of these wheels is provided with a transfer tooth 45 which is in the position shown in Fig. 4 when the totalizer wheel to which it is attached stands at zero or in the position shown in Fig. 5 when its totalizer wheel stands at 9.

35 It will be remembered that the shaft 28 is rotated approximately 324 degrees as the totalizer wheels 43 are being brought into mesh with the actuating segments 30.

This shaft 28 is provided with a cam 46 (Fig. 40 5) which is rotated clockwise as viewed in Fig. 5 until it engages the left hand end of a lever 47, rotating the said lever counter-clockwise. This lever is pivoted on the bar 42 and carries a pin 49 in a depending arm, which pin is connected to a plate 50 integral with a holding member 51 which underlies all of the transfer arms 52 pivoted on a shaft 53.

An arm 48 is pivoted on the bar 42 and is pulled downwardly by means of a spring 54. This 50 arm 48 is provided with a shoulder 55 and the transfer arm 52 is provided with an arm 56 so that when the transfer arm 52 is raised by the cam 46 the upper end of the arm 56 will be just above the shoulder 55 and the arm 52 will be 55 held in its partly elevated position by the holding member 51 holding the nose 66 just above the teeth of the totalizer wheels 43. The arm 52 is provided with a pin 57 which carries a transfer pawl 58 which is urged towards the totalizer 60 wheel 43 by means of a spring 59. A lever 60 is pivoted on a shaft 61 and at its other end is provided with a bifurcation which receives the pin 57. This lever 60 is provided with a transfer lug 62 which is adapted to be engaged by the 65 transfer tooth 45. It will, of course, be understood that there are as many transfer arms and associated mechanisms as there are totalizer wheels with the exception of the over-flow wheels and with the further exception that there is 70 only one holding member 51 which contacts with all of the transfer arms 52.

As soon as the machine commences its operation the totalizer wheels 43 are moved into mesh with the actuating segments 30 as heretofore described, which movement is accomplished by the

roller 32 engaging the edge of the cam race 31. Almost immediately thereafter the cam race 10 raises the bar 14 which rotates the cam shaft 28 clockwise for approximately 324 degrees so that the cam 46 engages the lever 47 raising the holding member 51 so that the upper end of the arm 56 is just above the shoulder 55 and raising the nose 66 of the arm 52 out of the path of movement of the teeth on the totalizer wheel 43. The actuating segments 30 are then rotated as is well known in the art thereby actuating the totalizer wheels 43. If any of the transfer teeth 45 should engage its transfer lug 62 the lever 60 would be raised and through its connection, by means of the pin 57, with the transfer arm 52, the said transfer arm will be rotated clockwise as viewed in Figs. 4 and 5 so as to bring the upper end of the arm 56 beneath the shoulder 55 and the spring 54 will pull the arm 48 downwardly so that as soon as the transfer tooth 45 passes beyond the transfer lug 62 the upper end of the arm 56 will engage the shoulder 55 and the transfer arm 52 will, therefore, be held in its elevated position. The cam race 31 then actuates the lever 34 and arm 41 so as to move the totalizer frame outwardly and disengage the totalizer wheels 43 from the actuating segments 30. The cam race 10 now lowers the bar 14 and rotates the cam shaft 28 in an anti-clockwise direction so as to release the cam 46 from the lever 47 whereupon the spring 63 connected to an extension of the arm 56 pulls downwardly any of the arms 52 which are not in their extreme elevated position caused by a transfer tooth having caused its arm 56 to be engaged by the shoulder 55 thereby rotating the holding member 51 to its home position. Any of the arms 52 which are now held in their extreme elevated position by its arm 56 engaging the shoulder 55 will continue to be held in this elevated position but immediately after the holding member 51 has been lowered, transfer cams 64 carried by the cam shaft 28 will engage surfaces 65 on the levers 60 thereby depressing the said levers 60. The upper end of the arms 56 will be cammed out from the shoulders 55 and these transfer arms 52, being now free, are moved downwardly by the cams 64 so that the transfer pawls 58 will engage the teeth of the totalizer wheel of next higher order and rotate it clockwise, as viewed in Figs. 4 and 5, a distance corresponding to one unit. Immediately thereafter the nose 66 of the arm 52 will engage the totalizer wheel 43 and lock it against further rotation which also prevents this wheel from being overthrown. The transfer cams 64 are staggered as 55 are shown in Fig. 5, there being as many such cams as there are transfer arms. This staggered arrangement is such that the transfer takes place from the units to the tens wheel and immediately thereafter the next cam 64, which might be called the tens cam, causes the actuation of the tens transfer arm which transfers from tens to hundreds and so on. It is to be noted that these cams will be positively actuated and do not rely for their function upon any spring or other yieldable connection. In describing the transfer mechanism as being positively actuated, it is intended to convey the idea that its function does not rely upon springs for the carrying movement of the transfer arm.

I have also provided a novel resetting mechanism for the totalizer which prevents the machine being operated when the resetting key is in place or while the resetting key is being turned and whereby the resetting key cannot be re-

15 moved from the totalizer until the totalizer has been completely reset. To this end I have provided a lever 67 which normally extends over the key hole 68 so that in order to insert the key 69 it is necessary to depress the lever 67. This lever 67 is pivoted on the shaft 21 and is provided with an extension 70 which underlies a pin 71 on a lever 72 pivoted on the shaft 19 and having an extension 73 which carries a pin 74 which engages 10 an arm 75 secured to a shaft 76. The shaft 76 also has secured thereto an arm 77 which carries a pin 78 secured to the upper end of a bar 79 which at its lower end is provided with a lug 80 adapted when depressed to engage a recess 81 in 15 a disk 82 secured to the shaft 5 so that if the lever 67 is pulled downwardly so as to insert the key, the shaft 5, and hence the crank 1, is locked against rotation.

20 An outer plate 83 is provided with a barrel 84 which receives the stem of the key 69 and is normally pressed outwardly by means of springs 85. When the key is positioned inwardly so as to overcome the tension of the springs 85 thereby moving the plate 83 inwardly a notch 86 thereof engages a stud 87 in a barrel 88 secured to a cam 89, a Geneva gear 90, Geneva disk 91, and ratchet 92. The cam 89 as will be noted in Fig. 3 is a circle except that at its upper portion as viewed in Fig. 3 it has a shorter radius than on the lower portion thereof. A pin 93 rides on the periphery of this cam 89 so that as the cam is rotated in a clockwise direction as viewed in Fig. 3 by means of the key this pin 93 will be raised. This pin 93 is carried by the lever 47 and by raising the pin 93 the holding members 51 are also elevated so as to disengage the noses 66 from the totalizer wheels so that the totalizer wheels can be reset. This pin 93 simply rides on the periphery of the cam 89 until the totalizer wheels have been reset, whereupon the shoulder 94 of the cam 89 passes beyond the pin 93 thereby releasing the lever 47 and the spring 63 thereupon pulls the arms 52 downwardly until they engage the shoulders 66 with the totalizer wheels 43. The Geneva gear 90 and Geneva disk 91, as is shown in Fig. 3, engage a Geneva pinion 95. This pinion is provided with one cut-away tooth and adjacent teeth 96 and 97 will normally engage the periphery of the disk 91 locking the pinion 95 against rotation. When, however, this disk 91 is rotated by means of the key the Geneva gear 90 engages a narrow tooth 98 of the Geneva pinion 95 and starts the Geneva gear 95 to rotating. It is then given one complete rotation and thereby drives the pinion 99 and the shaft 44 to which it is secured one complete revolution. The shaft 44 is provided with resetting pawls 100, there being one such resetting pawl for each totalizer wheel, which pawl engages notches 101 in the totalizer 55 wheels and resets them to zero position.

A disk 102 is also secured to the shaft 44, which disk is provided with a notch 103. The normal position of this notch is shown in Fig. 5. A lever 104 is pivoted to a shaft 105, which lever has a nose 106 which normally rides on the periphery of the disk 102. At its other end the lever 104 is pivoted to the shaft 61 which is also the shaft on which the lever 60 is pivoted. When the parts are in the position shown in Fig. 5 it is utterly impossible to rotate one of the totalizer wheels by means of a screw driver or other tool because the nose 66 of the arm 52 is projecting between two adjacent teeth of the totalizer type wheel and preventing rotation in a clockwise direction as viewed in Fig. 4 and the pawl 58 prevents rotation.

in an anticlock direction as viewed in the said figure. The surface 110 (Fig. 7) of the lever 52 is lying directly beneath the cam 64, which cam extends so closely adjacent the surface 110 that it would be impossible to raise the lever 52 a sufficient distance to permit the nose 66 to clear the teeth of the totalizer wheels 43. This construction absolutely locks the totalizer wheels against unwarranted manipulation.

The transfer tooth 45 as shown in Fig. 5 is in its ninth position and in Fig. 4 it is in its zero position. It is, therefore, apparent that this transfer tooth will pass beneath the transfer lug 62 on the last part of the resetting movement of the shaft 44. As the transfer tooth 45 reaches the transfer lug 62 the notch 103 is adjacent the nose 106 of the lever 104 and the spring 111 pulls the nose 106 into the notch 103 thereby rotating the lever 104 clockwise around its pivot 105 thereby elevating the shaft 61 and thereby raising the left hand end of the lever 60 as viewed in Fig. 4 so as to raise the transfer lug 62 out of the path of movement of the transfer tooth 45. As soon as the transfer tooth 45 has moved from the position shown in Fig. 5 to that shown in Fig. 4, in which latter case it is at its reset or zero position. The nose 106 is cammed out of the notch 103 so that the lever 104 is rotated anti-clockwise, thereby lowering the shaft 61 and lever 60 so that the transfer lug 62 is again in its normal position. Preferably there are two such disks 102 and two levers 104 on opposite sides of the machine, whereas the shaft 61 connects all of the levers 60 so that all of the levers 60 are raised as above described when the transfer tooth is passing from its ninth to its zero position. In the regular adding operation it will be remembered that the lever 52 is raised so as to permit the transfer tooth passing beneath the transfer lug 62 and it is only on the resetting operation that it is necessary to elevate the shaft 61.

A spring 107 urges a pawl 108 into engagement with the ratchet 92 so as to prevent the key being turned in an anti-clockwise direction as viewed in Fig. 3. When the rotation is completed the 45 springs 85 will position the key 69 outwardly so that it will engage a key hole in the fixed bar 109 so that further rotation is impossible.

It is, therefore, apparent that in order to insert the key it is necessary to pull downwardly on the lever 67 and this movement locks the machine against operation. It is furthermore apparent that the key is ejected after the totalizer wheels are reset.

I realize that many changes may be made in the specific form of this invention shown and described by way of illustration in this application and I, therefore, reserve the right to make such changes in the specific form of the invention as shown herein as I may find to be desirable. I, therefore, claim the invention broadly except as I may limit myself by the appended claims. 55 60

Having now described my invention, I claim:

1. In a register, totalizer wheels, transfer levers whereby a wheel of lower order will control the actuation of the wheel of next higher order on a carrying operation, cam means whereby said levers are raised initially each time the machine operates, cam means to raise any one or more of said levers a greater distance if a transfer operation is involved, and cam means to depress all of said levers to their initial position and hold said levers in their depressed position until the register is either again operated or the totalizer is reset. 75

2. In a register, totalizer wheels, transfer levers whereby a wheel of lower order will control the actuation of the wheel of next higher order on a carrying operation, cam means to raise any lever 5 which will carry on that operation to a greater extent than the levers which will not carry on that operation, and cam means to depress all of said levers to initial position and hold said levers in their depressed position until the register is either 10 again operated or the totalizer is reset.
3. In a machine having a carrying mechanism, a carrying arm, a totalizer wheel, means whereby said arm is moved a predetermined distance on each operation of the machine, means whereby 15 said arm is moved an additional distance when the totalizer wheel moves from its maximum number position to its zero position, a cam, and means whereby said cam thereafter engages said arm so as to positively move said arm to its initial 20 position and lock it in the initial position.
4. In a machine having a carrying mechanism, totalizer wheels, means whereby said carrying mechanism adds a unit to one of the totalizer 25 wheels after the totalizer wheel of next lower order has passed to its zero position, means whereby said carrying mechanism normally locks all of said totalizer wheels against any movement and means to prevent rendering the last named 30 means inoperative unless the machine is being operated or the totalizer is being reset.
5. In a carrying mechanism, a cam, a totalizer wheel, means whereby said cam actuates said totalizer wheel when carrying, and means whereby said cam normally locks said totalizer wheel 35 against being moved by any tool.

6. In a machine, a carrying mechanism including a totalizer wheel, a resetting mechanism for said totalizer wheel, locking means forming a part of said carrying mechanism whereby said totalizer wheel is normally locked against any movement, means to prevent rendering the last named means inoperative unless the machine is being operated or the totalizer is being reset, and means whereby when either the machine or the resetting mechanism is operated said locking 10 means is rendered inoperative.

7. In a machine, an operating mechanism, a totalizer wheel, a key operated resetting mechanism, a carrying mechanism, means controlled by 15 the resetting mechanism to move a part of said carrying mechanism out of engagement with said totalizer wheel shortly after the resetting mechanism commences its operation, and means to remove another part of said carrying mechanism 20 out of engagement with said wheel when the resetting mechanism has almost completed its operation.

8. In a register, a totalizer wheel, an arm, a carrying pawl mounted on said arm and serving 25 as a means to actuate said totalizer wheels on a carrying operation, a nose forming a part of said arm, said nose and pawl serving as a means to prevent said wheel being rotated when said machine is not in use, and means normally locking said arm against being moved sufficiently to disengage said nose and pawl from said totalizer 30 wheel.

ALBERT S. WHEELBARGER. 35
